SIGNORS, BY MESNE ASSIGNMENTS, TO FEDERAL TELEGRAPH COMPANY, OF SAN
FRANCISCO, CALIFORNIA, A CORPORATION OF CALIFORNIA.

MULTIPLEX RADIO SYSTEM.

Application filed January 9, 1922. Serial No. 527,883.

To all whom it may concern:

Be it known that we, HAROLD F. ELLIOTT and JAMES ARTHUR MILLER, citizens of the United States, and residents of Palo Alto, in the county of Santa Clara and State of California, have invented a new and useful Multiplex Radio System, of which the following is a specification.

This invention relates to a multiplex radio transmitting system, utilizing more than one antenna.

It is often desirable to operate a plurality of transmitters for radio signaling from the same building, so as to economize in space and in the number of employees. Since each transmitter is associated with its own antenna, the result is that a plurality of antennæ are placed near each other. This usually has the objectionable effect that there is more or less capacitive or electrostatic coupling between them. Due to this coupling, the two transmitter circuits are to some extent inter-dependent. While in some types of transmitters, such a condition is not serious, it has been found that an objectionable interference between the circuits results when arc converters are used as the generators of radio frequency. It is one of the objects of our invention to render the operation of such transmitter circuits substantially independent of each other, so that signals may be sent from any one of them without danger of interference from any of the others. Another object of our invention is to render it possible to start or stop any of the transmitters without influencing the operation of the other transmitters.

The invention possesses other advantageous features, some of which, with the foregoing, will be set forth at length in the following description where we shall outline in full those forms of the invention which we have selected for illustration in the drawings accompanying and forming part of the present specification. Several embodiments of our invention are shown in the drawings, but it is to be understood that we do not limit ourselves to such forms, since the invention as expressed in the claims may be embodied in other forms as well.

Referring to the drawings:

Fig. 1 is a wiring diagram of a system embodying one form of our invention; and

Figs. 2 and 3 are wiring diagrams showing further modifications.

55

In the following discussion systems will be described each using only two transmitters operating at substantially different frequencies, but it is to be understood that the schemes elucidated are fully as applicable to 60 systems using any number of transmitters.

One of the schemes by which it is possible to overcome the disturbing effects of one source upon another is illustrated in Fig. 1. To obtain this result, we arrange matters in such a way that the antenna system of each transmitter has a relatively high impedance at the frequencies of the other transmitters, and this relatively high impedance is not substantially altered by the starting or stopping 70 of the transmitters, or whether signals are sent or not.

The establishment of a high impedance for interfering currents may be accomplished in the following manner:—The arcs 35 and 36 or other sources of high frequency current, are arranged to feed the transmitting circuits 13—14—15 and 18—19—20 respectively. In series with arc 35 are placed the inductor 37 and condenser 38; in series with arc 36 are placed the inductor 39 and condenser 40. These elements are all in series in the antenna circuits. The circuit consisting of arc 35 inductor 37 and condenser 38 is tuned to the frequency of transmission of the associated antenna circuit; and the circuit consisting of arc 36, inductor 39 and condenser 40 is similarly tuned to the frequency of transmission of the associated antenna circuit. Paralleling each of these tuned circuits is a 90

circuit consisting for example of a resistor 41 or 42. This resistor serves to by-pass and damp out harmonics or other objectionable current that would otherwise be present in the circuits. Since each antenna circuit is tuned to its own frequency, the impedance of either of them such as 18—19—20 is comparatively large for currents of frequencies differing substantially from its own. Thus currents induced in this antenna circuit by current flowing in the antenna circuit 13—14—15 are relatively low in value. The interfering current that can pass through the tuned circuit 40—39—36 is still lower, 105 since its impedance is also high for frequencies other than its own. The voltage in-

duced across this circuit is also low, and thus the operation of the two sources 35 and 36 on adjacent antennae do not interfere with each other. The by-pass action of resistors 5 41 and 42 not only limits the operation of the sources to certain definite frequencies, but also permits the interfering currents from the adjacent antenna to be conducted to ground without passing through the 10 source. Other forms of impedance may, of course, be substituted for the resistors. The operation of such by-pass circuits to limit the source to a definite frequency is described and claimed in an application in 15 our names, filed concurrently herewith, entitled "Radio frequency system," Serial No. 527,884.

Somewhat similar principles of operation to those just described, are utilized in the 20 form of our invention illustrated in Fig. 2. In this form, means are also provided for increasing the efficiency of the source, which may be an arc or bulb, by controlling the point at which it operates on its current 25 voltage characteristic. In the figure there are shown the two arcs or other sources 43 and 44, supplying respectively the antenna circuits 13—14—47—45 and 18—19—48—46. The antenna circuits are closely coupled by 30 means of coils 47 and 48 to their respective sources. Thus arc 43 supplies radio frequency current to a circuit consisting of the inductor 49, condenser 50, coils 51 and 52, and the coils 53 and 47. The coils 53 and 47 35 form an air cored auto transformer, the coil 47 forming a portion of the secondary circuit supplying the antenna. It is of course possible to substitute a conventional transformer for the auto transformer 47—53. 40 The arc circuit between point 54 and ground 55 is tuned to the frequency which it is desired to use, the inductor 49 and condenser 50 being in the circuit for the purpose of tuning. The resistor 56 or other form of 45 impedance is connected across this tuned circuit. The operation of this system to increase the efficiency of the source and to confine its operation to a definite frequency is described and claimed in another application in our names, filed concurrently herewith, entitled "Radio frequency system," Serial No. 527,885.

In order to neutralize whatever coupling 50 there may be unavoidably present between the inductor 49 and the transformer coils 53 and 47, the coils 51 and 52 are coupled to the proper extent. This is especially useful when uniwave signaling is used, since if the coupling is not neutralized, a small 60 amount of energy may still be radiated although no signal is supposed to be sent. Uniwave signaling may be readily accomplished by short circuiting the resistor 56 to stop the sending of waves. For this purpose 65 relay keys 57 and 58 may be closed. To keep

the load on the source constant, a secondary circuit may be coupled to the inductor 49, consisting of the coil 59 and resistance 60. This circuit is open when waves are sent, but may be closed simultaneously with the 70 closing of keys 57 and 58, by means of key 61. It is possible to regulate the amount of energy dissipated in circuit 59—60—61 either by properly choosing the value of resistance 60 or by varying the degree of coupling between the coils 49 and 59. The resistor 56 in connection with the tuned local circuit and the tuned antenna circuit effectively by-passes the interfering currents, as explained in connection with Fig. 1. The 80 source is also confined to operation at the correct frequency without higher harmonics. Due to the transformer action, the current in the intermediate or primary circuit is lower than would be the case without the use of 85 the transformer action. The result is not only a reduction in the losses in this circuit, but also in the size, weight and cost of such apparatus as the inductor 49 and condenser 50 in this circuit. Thus the use of this system 90 renders practicable the operation of filter circuits with high power transmitters. The elements shown in the system connected to the other antenna 18 are entirely similar 95 to those described in connection with antenna 13.

In Fig. 3 is shown a simpler scheme for preventing interference between transmitting systems. In this case a resistor 64 and a stopping condenser 65 are shunted around the source 62 and serve to by-pass the objectionable interfering currents. The stopping condenser 65 prevents current from the generator 16 from being wasted through the resistor 64. The other antenna 18 is supplied from a system including a source of high frequency oscillations 63, and other elements equivalent in every way with those just described in connection with antenna 13.

We claim:

1. In a multiplex radio frequency transmission system, a plurality of antenna circuits, each adapted to be independently operated at frequencies that differ substantially, and each having an antenna that is placed near the others, sources for producing high frequency oscillations in each of the antenna circuits, and means for preventing substantial interference between the circuits, comprising a circuit for each source forming a by-pass, said circuit being connected between points having minimum potential difference for the frequency of operation of the source with which it is associated.

2. In a multiplex radio frequency transmission system, a plurality of antenna transmitting circuits, each adapted to be independently operated at frequencies that differ substantially and each having an antenna that is placed near the others, means for

producing oscillations in each antenna circuit, and means for preventing substantial interference between the circuits, comprising an energy consuming device for each 5 transmitting circuit, and means for connecting said device in each circuit so that it may conduct the interfering current from the other transmitting circuit around the source of oscillations.

10 3. In a multiplex radio telegraphy system, a plurality of antenna circuits having substantially different frequencies and having antennæ near one another, sources for producing high frequency oscillations in each of 15 the antenna circuits, and a by-pass circuit for each source, whereby substantially all currents produced by interference of any

of the other sources is passed through these by-pass circuits.

4. In a multiplex radio telegraphy system, 20 a plurality of antenna circuits having substantially different frequencies and having antennæ near one another, sources for producing high frequency oscillations for each of the antenna circuits, a circuit connected in series between each antenna circuit and its source, the source and this circuit being tuned to be resonant at the frequency of the source, and a circuit in each antenna system 25 bridging this resonant circuit. 30

In testimony whereof, we have hereunto set our hands.

HAROLD F. ELLIOTT.
JAMES ARTHUR MILLER.
